MIXING DEVICE

James L. Walker, Baytown, Tex., assignor to
Standard Oil Development Company, a corpora-
tion of Delaware

Application July 3, 1944, Serial No. 543,306

4 Claims. (Cl. 259—4)

The present invention is directed to a device for contacting fluid substances.

More particularly, the present invention is directed to a mixing device for fluids which is capable of adjustment for regulating the amount of turbulence produced when the rate of flow of fluid through the device is maintained constant or for maintaining constant the amount of turbulence produced when the rate of flow of fluid through the device is variable.

The present invention may be described briefly as a mixing device involving a shell or body in which are arranged a number of mixing plates with means to alter the position of the plates in the shell and thereby control the number of mixing plates through which the fluid being passed through the mixing device is forced to flow.

Other objects and advantages of the present invention may be seen from a reading of the following description taken with the drawing, in which:

Fig. 1 is an elevation, partly in section, of one embodiment of the present invention showing the mixing plates all in position to allow bypassing of the plates by fluid flowing through the shell, that is, with a minimum pressure drop through the incorporator;

Fig. 2 is a view of the embodiment of Fig. 1 with the position of the plates altered to force the fluid to flow through one of the plates;

Fig. 3 is another view of the same embodiment with the mixing plates in position to force fluid flow through each of the plates, that is, in position to cause maximum turbulence;

Fig. 4 is a view of another embodiment of the present invention having a divided flow through the incorporator to eliminate excess thrust on the shaft carrying the mixing plates, and with the mixing plates shown in position to cause minimum turbulence; and

Fig. 5 is another embodiment of the present invention similar to that of Fig. 1, but showing pierced cones substituted for the pierced plates for the mixing elements and with the cones adjusted to require flow through all of them; and

Fig. 6 is a fragmentary view of another embodiment of mixing elements.

Turning now specifically to the drawing, and first to Fig. 1, the incorporator has a cylindrical shell 11, with a plate 12 closing one end and a plate 13 the other end. An inlet line 14 is provided through plate 12 and an outlet line 15 leads from the end of the shell adjacent plate 13. Within shell 11 are arranged spaced bushings 16, 17, 18 and 19. These bushings are of proper

diameter to have their outer surface contacting snugly with the inner surface of shell 11. These bushings are of successively greater width; that is to say, bushing 16 is the narrowest, bushing 17 is somewhat wider than bushing 16, bushing 18 is wider than bushing 17, and bushing 19 is the widest of the group.

Within the incorporator shell is rod 20, coaxial with the shell and maintained in position by guides 21 and 22, which are secured respectively to end plates 12 and 13. End plate 13 is provided with a suitable packing 23 to prevent the leakage of fluid at this point. The end of the rod extending above end plate 13 is provided with a screw thread 24 and a keyway 25. Secured to end plate 13 and embracing rod 20 is annulus 26, carrying key 27. A hand wheel 28 is carried by annulus 26. The arrangement of the hand wheel, screw thread and key at the end of the incorporator allows the rod to be moved longitudinally with respect to the shell 11 at the option of an operator.

Within shell 11 and spaced along rod 20 are disks 29, 30, 31 and 32, provided with perforations 9. These disks extend transversely with respect to the incorporator shell and have a diameter slightly less than the inside diameter of bushings 16, 17, 18 and 19. The spacing of the bushings and the pierced disks is such that as rod 20 is moved, the edges of the disks come in opposition successively with the corresponding bushings.

In Fig. 1, none of the disks is in opposition to a bushing, and the fluid passing through the incorporation may flow around each of the mixing disks, so that all the disks may be said to be bypassed by the fluid, although a relatively small amount of fluid will take a path through the perforations of the disks. Upon the rotation of hand wheel 28, the disks may be brought into opposition to the bushings, with disk 32 first brought into opposition with bushing 19, then additional disk 31 brought into opposition with bushing 18, then additional disk 30 brought into opposition with bushing 17, and finally disk 29 brought into opposition with bushing 16, to place each disk in the mixing device in opposition to its respective bushing. Fig. 2 shows the device adjusted with disk 32 in opposition with bushing 19, while Fig. 3 shows the device with all of the disks brought into opposition with their respective bushings. While some turbulence results when the fluids are forced to pass through the annular space between the shell and the disks, this turbulence is relatively small compared with

that produced when all of the fluid is forced to flow through the relatively small perforations of the disks. The amount of turbulence or degree of mixing at a given rate of fluid flow is roughly proportional to the number of disks brought into opposition with the bushings of the device.

Another embodiment of the present invention is shown in Fig. 4. In this embodiment the fluid to be mixed is divided into two streams, with the streams forced to flow in opposite directions through the incorporator. This arrangement reduces or eliminates fluid thrust on the rod carrying the mixing plates. In this embodiment shell 40 is provided with an inlet 41 conducting fluid into a central portion of the shell, and is provided with outlets 42 and 43 for removing fluid from each end of the shell. The outlets 42 and 43 discharge into conduit 44.

One end of shell 40 is provided with spaced bushings corresponding to those of Fig. 1 and hence given identical numbers, being designated as bushings 16, 17, 18 and 19. The other end of the mixing shell is provided with bushings spaced away from the inlet in the same manner as in the end previously described and hence are designated by numerals 16', 17', 18' and 19'. Rod 20' extends longitudinally through the shell and terminates with a threaded end and hand wheel 28 to allow the adjustment of this rod in the same manner that rod 20 is adjusted in Fig. 1. Secured to rod 20' are transversely extending mixing disks 29, 30, 31 and 32 arranged to be brought into opposition respectively with bushings 16, 17, 18 and 19, and disks 29', 30', 31' and 32' arranged to be brought into opposition with bushings 16', 17', 18' and 19'.

In the embodiment of Fig. 4 the longitudinal movement of rod 20' causes pairs of mixing disks to be brought simultaneously into opposition with pairs of bushings. For example, with the device adjusted as shown in Fig. 4, fluid flowing through the incorporator may bypass all of the mixing disks. Movement of the end of rod 20' carrying screw thread 24 away from body 40 first brings into opposition plate 32 with bushing 19 and plate 32' with bushing 19'. Continued movement of rod 20' brings into opposition plates 31 and 31' with bushings 18 and 18' respectively, then in succession pairs of mixing plates 30 and 30' are brought into opposition with bushings 17 and 17' and plates 29 and 29' in opposition with bushings 16 and 16'.

The embodiment of Fig. 5 is similar to that of Fig. 1, with the exception that the mixing disks have been replaced by double cones 49, 50, 51 and 52. It will be understood that this embodiment may be provided with means for moving rod 20 longitudinally including a hand wheel and screw thread, as are the precedingly described embodiments, but in order to simplify the drawing, a showing of such means has been omitted from this figure. These cones are provided with perforations 53, corresponding to perforations 9 of the mixing disks previously described. The mixing cones of the embodiment of Fig. 5 may be brought into opposition with corresponding bushings 16, 17, 18 and 19 by movement of the rod 20 in exactly the same way as in the embodiments previously described.

Another arrangement of mixing means is shown in the fragmentary view Fig. 6. In this view the mixing elements are cones 59, 60, 61 and 62, secured to rod 20 and provided with perforations 63. This assembly of mixing cones may be arranged in the shell of an incorporator in exactly the

same way as the pierced plates of the embodiment of Fig. 1 or the pierced double cones of the embodiment of Fig. 5. It will be understood that the number and size of the holes of the elements employed to produce turbulence in mixing may be varied as desired.

It will also be understood that the last plate to come in opposition with the bushing in the adjustment of the device, that is, plate 29 of the embodiment of Fig. 1, may, if desired, be without perforations. When a solid plate of this type is provided, the rate of flow through the incorporator may be substantially zero, and in this way efficient mixing at very low rates of fluid flow may be obtained. It will also be evident that while embodiments with bushings 16, 17, 18 and 19 of differing widths and spacing and plates 29, 30, 31 and 32 of equal width and spacing have been shown in the drawing, an arrangement with bushings 16, 17, 18 and 19 of uniform width and unequal spacing and with plates 29, 30, 31 and 32 of equal width and spacing is equivalent thereto. Similarly, the widths and spacing of the bushings and the plates may be reversed, and the bushings may be uniform in width and equally spaced, while the spaces between the plates are unequal.

It will be seen that I have disclosed a mixing device which may be positively adjusted by an operator to give the desired amount of turbulence to fluids being admixed over a wide range of rate of flow. While I have disclosed specific embodiments of the present invention, it will be apparent that details of the device may be altered without departing from the scope of the invention, and it is my intention to embrace such changes in the hereto appended claims.

I claim:

1. A contacting device for fluid substances comprising, in combination, an elongated tubular shell provided with an inlet means and an outlet means, a plurality of bushings of differing widths spaced in said shell between the inlet means and the outlet means, with the outside surfaces of said bushings in contact with the inner surface of the shell, a rod arranged in the shell coaxial therewith and longitudinally movable from a first position to a second position, perforated baffles carried by said rod, said baffles being equal in number to the bushings in the shell and slideable in the bushings and spaced on the rod so that when the rod is in its first position none of the baffles is adjacent a bushing, but as the rod is moved from its first to its second position an increasing number of the baffles is brought in opposition to the bushings.
2. A contacting device for fluids comprising, in combination, a tubular shell having an inlet adjacent one end and an outlet adjacent the opposite end, a plurality of bushings in said shell, said bushings being of equal inside and outside diameter and of progressively increasing widths and spaced in the shell with the outside surfaces in contact with the inside surface of the shell and with the distances separating adjacent bushings increasing as the width of the bushings decreases, a rod coaxial with the shell longitudinally movable from a first position to a second position, a plurality of perforated baffles with a diameter slightly less than the inside diameter of the bushings secured to said rod and spaced so that when the rod is in the first position no baffle opposes a bushing, but as the rod is moved from its first to its second position an increasing number of baffles is progressively brought in opposition to the bushings.
3. A contacting device for fluid substances com-

prising, in combination, a tubular shell having an inlet at a medial point thereof and a first outlet for the removing liquid from one end and a second outlet for removing liquid from the other end thereof, a first set of bushings of uniform inner and outer diameter and of progressively increasing widths spaced in the shell between the inlet and the first outlet with the distance between adjacent bushings decreasing as the width of the bushings increases from the inlet to the first outlet and with the outer surfaces of the bushings in contact with the inner surface of the shell, a second set of bushings corresponding in number and dimensions to the first set of bushings spaced in the shell between the inlet and the second outlet with the distance between adjacent bushings decreasing as the width of the bushings increases from the inlet to the second outlet, a rod arranged in the shell coaxial therewith and longitudinally movable from a first to a second position, a first and a second set of perforated baffles carried by the rod, said baffles having a diameter slightly less than the inside diameter of the bushings and slideable therein and spaced along the rod so that when the rod is in its first position none of the baffles opposes a bushing, but as the rod is moved from its first to its second position the number of the first set of

baffles opposing the first set of bushings and the number of the second set of baffles opposing the second set of bushings increases progressively and equally.

5. 4. A contacting device comprising, in combination, an elongated shell defining a longitudinally extending passage including sections of enlarged flow area and at least two spaced sections of reduced flow area and an inlet and an outlet separated by said spaced sections of reduced flow area, a rod in the shell parallel with the axis of the passage and movable progressively in a longitudinal direction from an initial position to a second and third position, a first perforated baffle plate mounted on said rod with its periphery defining a boundary fitting slidably within one of said sections of reduced flow area when the rod is in its second and third positions and lying in a section of enlarged flow area when the rod is in its initial position, a second perforated baffle plate mounted on said rod with its periphery defining a boundary fitting slidably within the other of said sections of reduced flow area when the rod is in its third position and lying in a section of enlarged flow area when the rod is in its initial and second positions.

JAMES L. WALKER.
